UNITED STATES PATENT OFFICE.

OSWALD S. PULLIAM, OF PITTSBURG, PENNSYLVANIA, ASSIGNOR TO PITTSBURGH EQUIPMENT COMPANY, OF PITTSBURG, PENNSYLVANIA, A CORPORATION OF PENNSYLVANIA.

CAR-TRUCK.

No. 861,766.

Specification of Letters Patent.

Patented July 30, 1907.

Application filed January 29, 1907. Serial No. 354,679.

To all whom it may concern:

Be it known that I, OSWALD S. PULLIAM, of Pittsburgh, in the county of Allegheny and State of Pennsylvania, have invented certain new and useful Improvements in Car-Truck Side-Frame Construction, of which the following is a specification.

The object of my invention is to provide a new and improved side-frame construction for car-trucks.

To this end the present invention consists of a side-frame construction, in the novel features of construction, and in the combination of parts all as hereinafter described and claimed.

In the accompanying drawing, which illustrates applications of my invention, Figure 1 is a part side elevational and a part sectional view of side-frame construction embodying my invention; Fig. 2, a plan of the form of Fig. 1; Fig. 3, a view similar to Fig. 1, showing a modified form of connecting means; Fig. 4, a part plan and a part sectional view of the form of Fig. 3; Fig. 5, a side elevational view of the box of Fig. 1; and Fig. 6, a similar view of the box shown by Fig. 3.

Referring to the drawing, 1 designates the side-frame proper which is preferably formed as an integral structure and of cast-steel. The side-frame is provided with a centrally disposed opening 2, to receive an end of a bolster, not shown.

3—3 represent axle-boxes made separate from the side-frame.

A characteristic and important feature of the present invention is the means for connecting the axle-boxes with the side frame whereby the said boxes and frames may be readily connected and disconnected from one another. In the drawing I show two forms of connection, both forms, however, have means formed integral with the axle-boxes adapted to engage means formed on the side-frame.

In the form of Fig. 1 each end of the side-frame is

provided with upper engaging-members 4 formed with a recess 5, and lower engaging-members 6 formed with a recess 7. The axle-boxes in this form are provided with a top wedging-member 8 and with a lower engaging flange 9. In assembling the parts the axle-boxes are inserted laterally in the side-frames, the member 8 being forced into position in the recess 5 of engaging-member 4 and the flange 9 into recess 7 of the lower engaging-member 6. 10 designates bolts connecting the top and bottom-members of the side-frame.

In the form of Fig. 3, the axle-boxes are provided on their sides with a vertically disposed wedging-member 11, and the side-frame formed with engaging-members 12, having a vertically extending recess 13. Recesses 13 are adapted to receive the wedging-members 11 of the boxes. 14 designates extensions on the boxes and are adapted to be turned down over the members 12 when the boxes are applied to the side-frames.

What I claim is:

1. In a side-frame construction for car-trucks, the combination with a side-frame proper, of independent axle boxes, connecting-means formed integral with the side-frame, a wedge-shaped member formed integral with each of the axle boxes, said connecting-means and members adapted to cooperate to lock the boxes to the side-frame. 60

2. In a side-frame construction for car-trucks, the combination with a side-frame proper having each of its ends provided with an upper engaging-member, a lower engaging-member, of independent axle boxes each formed with an upper wedge-shaped member adapted to engage an upper engaging-member of the side-frame and a lower engaging-member adapted to engage a lower engaging-member of the side-frame. 70

In testimony whereof I affix my signature in presence of two witnesses.

OSWALD S. PULLIAM.

Witnesses:

MARGARET HUGHES,
W. G. DOOLITTLE.
